UNITED STATES PATENT OFFICE.

KARL VÖLLER, OF DUSSELDORF, GERMANY, ASSIGNOR TO RHEINISCHE METALL-WAAREN- UND MASCHINENFABRIK, OF DUSSELDORF-DERENDFORF, GERMANY, A CORPORATION OF GERMANY.

SETTING-KEY FOR FUSES.

1,104,585.

Specification of Letters Patent. Patented July 21, 1914.

Application filed October 14, 1913. Serial No. 795,128.

To all whom it may concern:

Be it known that I, KARL VÖLLER, a subject of the German Emperor, residing at 12 Scharnhorststrasse, Dusseldorf, Germany, have invented certain new and useful Improvements in Setting-Keys for Fuses; and I do hereby declare the following to be a full, clear, and exact description of the invention, such as will enable others skilled in the art to which it appertains to make and use the same.

The invention relates to a setting key for fuses with a correction device, which enables the fuses of a number of projectiles to be set to different lengths in the shortest possible time.

This is effected according to the invention by attaching the member which sets the correction to the hand grip, so that the adjustment can be effected with the hand which holds the setting key. The member for effecting the correction is displaced during the setting through a certain distance and is then held in this position by a locking device. After a certain number of projectiles has been set by the displacement of this member, the locking device is released by a spring and the member returned to its original position.

10 A setting key with a correction device according to the invention is represented in the accompanying drawing in which:—

Figure 1 is a section through line 1—1 of Fig. 2. Fig. 2 is a plan view. Figs. 3 and 4 are sections respectively through lines 3—3 and 4—4 of Fig. 2.

The setting key has the same construction as that shown in the United States Patent No. 1037811.

0 *a* is the hand grip to which the ring *b* is secured. The ring *b* is surrounded by a second ring *c* having a flange *d* with which ring *b* is in contact. A flange *e* screwed in the ring *c* retains the two rings *b* and *c* together and allows them to be relatively rotated, but not vertically displaced. On the ring *c*, which carries a fixed stud for setting the fuse, there is a graduated ring *f* and the ring *b* has a mark which can be set to 5 the length required for the fuse.

In the ring *b* there is a slide *g* which can be adjusted and fixed in position and carries a second projection *h* for setting the

fuse. The slide is moved by a member *k* which is journaled in an extension *i* of the grip *a*, and when the latter is held in the hand can be displaced by the pressure of the thumb on the roughened knob *l*. The connection between the slide *g* and the member *k* which effects the setting is established by a pin *m* which engages in a slot in the member *k*. The member *k* is provided on one part with teeth *n* with which a detent *o* is forced into engagement by a spring, so that a displacement can only occur in a definite direction against the pressure of a spring *p*. On pressing the knob *l* the slide *g* is displaced through the space of one tooth. The distance apart of the teeth is such, that the slide *g* and the projection *h* on it are displaced by the amount corresponding to the required correction. When the member *k* reaches the end of its travel it will be returned to its normal position by the pressure of the spring *p* after the locking device *o* is released. The locking device *o* is released by pressing on its outwardly projecting head, whereby the part engaging in the teeth of the member *k* is moved back, so that the spring *p* can return the setting member to its normal position.

I claim as my invention:—

1. In a setting key having a hand grip, a corrective element for engaging with the setting ring of a fuse, and a longitudinally movable member mounted adjacent to the hand grip and connected to said corrective element for setting the latter.

2. In a setting key having a hand grip, a corrective element for engaging with the setting ring of a fuse, a spring-pressed longitudinally movable member mounted adjacent to the hand grip and connected to said corrective element, and means for holding said longitudinally movable member in different positions, the spring of said member returning it to its normal position when released from said holding means.

3. In a setting key having a hand grip, a corrective element for engaging with the setting ring of a fuse, a longitudinally movable member mounted adjacent to the hand grip and connected to said corrective element, said member having teeth in one side, a spring placed under tension as said mem-

ber is moved to actuate said element, and
a spring-pressed lock for engaging said
teeth for holding said member in its dif-
ferent positions, said member being re-
5 turned to its normal position by said spring
when released from said lock.

In testimony whereof, I have signed this

specification in the presence of two sub-
scribing witnesses.

KARL VÖLLER. [L. S.]
